ICE TRAY GRID

Clifford R. Carney, Miami, Fla., assignor to Cellon Corporation, Miami, Fla., a corporation of Florida

Application August 8, 1945, Serial No. 609,524

13 Claims. (Cl. 62—108.5)

1

The present invention relates to ice tray grids and more particularly to ice tray grids which are removable from an ice tray, and which may be readily operated to secure the release of the ice cubes therefrom.

The problem of freeing ice cubes from a tray in which they are frozen in a conventional type of mechanical refrigerator is one which has been long present in this art. The attempts to solve the problem have generally taken one of two directions. First, the provision of a grid formed of a resilient material, such for example as rubber or the like, which may be distorted to break the bond between the grid and the cubes, and thus to free the cubes from the grid. Second, the provision of a grid having rigid partitioning members, certain of which are movable relative to the others for the purpose of breaking the adhesion between the ice cubes and the rigid elements of the grid construction.

In both general forms of the prior grids the grid mechanism and the ice when frozen presents a rigid mass in which the grid, whether resiliently flexible or whether mechanically united for movement of one rigid section relative to the other is held immobile in the ice block. In both types of grids there is a mechanical connection which imparts structural rigidity to the grid member and this rigidity is further increased when the ice is frozen therein. In the case of the resilient types of grids, the resiliency of the material is much impaired and frequently lost at the low temperatures necessary for the freezing of the ice. The adhesion of the ice to the various portions of the rigid grid members in the type utilizing rigid members which are movable relative to one another, renders these grids immobile to the extent that they are for all practical purposes a rigid grid structure at the beginning of the ice removing operation. In order to satisfactorily break such grids from the ice cubes, it is necessary to apply a force thereto of sufficient magnitude to move one of the grid members relative to the other grid members, and having thus initiated the ice-freeing movement, to then follow it with the progressive movement of other of the grid members. This is frequently referred to in this art as a "progressive flow of power".

As distinguished from previously known types of grids, the grid of the present invention is com-

posed of a plurality of separate elements freely joined together in such a manner that a sudden force applied to any grid member is transmitted throughout the frozen grid and ice block to provide an instantaneous release of all of the ice cubes from the grid.

2

An object of the present invention is, therefore, to provide an ice tray grid structure having a plurality of grid members each being movable relative to all other parts of the grid and loosely held in assembled relation by an elongated assembly pin.

A further object of the present invention is to provide an ice tray grid structure in which the longitudinal separator is formed of a plurality of independent articulated segments each of which is independently movable relative to the other segments forming the longitudinal member, and each of which is relatively movable relative to the cross-members.

15 A further object of the present invention is to provide an ice tray grid structure in which the longitudinal separator is formed of a plurality of independent articulated segments each of which is independently movable relative to the other segments forming the longitudinal member, and each of which is relatively movable relative to the cross-members.

20 A further object of the present invention is to provide an ice tray grid formed of a plurality of separate rigid elements so united in the assembled structure that each element is relatively movable with respect to the other elements making up the composite structure, and in which relative movement is initiated in the grid while frozen in an ice block by a downwardly directed flow, the shock of which is readily transmitted through 25 the grid to the ice block as a whole, resulting in the instantaneous fracture of the block and the ready release of the ice cubes.

25 It is a further object of the present invention to provide an ice tray grid constructed of a plurality of separate rigid grid elements flexibly united for relative movement of any part relative to every other part in all directions, the cross-pins and the longitudinal members having substantially complete freedom of movement in any direction within predetermined limits whereby 30 a shock transmitted to the grid while frozen in an ice block is readily transmitted throughout the entire structure, resulting in the ready fracture of the ice block into a plurality of separate cubes, and the instantaneous release of the grid structure therefrom.

35 Other objects of this invention will appear in the following description and appended claims, reference being had to the accompanying drawings forming a part of this specification wherein

like reference characters designate corresponding parts in the several views.

In the drawings:

Fig. 1 is a view in perspective with parts broken away of an ice tray grid embodying the present invention.

Fig. 2 is a cross-section of the grid shown in Fig. 1, and through an ice tray pan into which the grid is to be placed.

Fig. 3 is a cross-section similar to Fig. 2 showing the grid in place in the ice tray.

Fig. 4 is a top plan view of the grid shown in Fig. 1.

Figs. 5 and 6 are enlarged fragmentary sections taken respectively on the lines 5-5 and 6-6 in the direction of the arrows, Fig. 4.

Before explaining in detail the present invention it is to be understood that the invention is not limited in the application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The grid construction here shown comprises a plurality of separate cross-members 10 and 11, having overlapping end portions provided with vertically extending projections 12 and 13, respectively. When assembled into a grid structure, they are spaced from each other longitudinally by a plurality of separate longitudinal spacer members 14, each of which is substantially L-shaped.

End members 15 and 16 are provided at each end of the grid structure and extend from the end cross-members 10 and 11 to the ends of the pan in which the grid is to be used. These members are shaped as required to fit the internal contour of the pan. The various elements of the grid construction are held in assembled relation by a longitudinally extending assembly pin 17, which extends through openings pierced in the short arm of the L-shaped end members 15 and 16, and the plurality of longitudinal members 14. The assembly rod 17 also extends through pierced openings provided in the cross-members 10 and 11. The relative sizes of the pierced holes and the assembly rod 17 are so selected that all parts are loosely held together and are movable relative to each other in all directions. As shown in Fig. 2 the cross-members 10 and 11 are free to move upward relative to the plurality of longitudinal members as is shown in Fig. 2. The grid is adapted to be dropped into a pan 18 which may be of any conventional design. When placed in the pan, the parts of the grid are held in position as indicated in Fig. 3 and serve to divide the interior of the pan into a plurality of separate compartments into which water is placed to be frozen into a block which is thereafter fractured to form ice cubes.

Assuming that the grid is frozen in position in the pan 18 as shown in Fig. 3, a sharp blow on the projection 12 or on the projection 13 in the direction of the arrows will cause the cross-members 10 and 11 to pivot in the directions indicated in Fig. 2. The shock is readily transmitted throughout the ice block and since the longitudinal connecting pin 17 and the pierced opening are located above the ice level as indicated by the line in Fig. 3, it will be seen that there is no mechanical connection between the separate elements of the grid which is rendered

rigid by the freezing of the ice therein. Thus the shock of the downwardly directed blow on the projecting members 12 and 13 is readily transmitted throughout the grid structure and causes the cross-members 10 and 11 to be moved relative to each other. The movement is transmitted simultaneously to the other separate elements forming the grid structure. It is to be understood that the amount of movement required to secure satisfactory cleavage of the ice from the grid structure is much less than that indicated in Fig. 2 for movement of very small magnitudes is all that is required to shear the adhering ice film from the grid members and to free the grid members from the ice block.

In constructing a grid of the present invention, I prefer to use a heat transmitting material, such for example as sheet aluminum alloys, magnesium alloys, or the like, the surfaces of which have been treated to render them non-adherent to water. One satisfactory method of accomplishing this is to subject the parts to treatment in an anodizing bath and thereafter to wax the anodized surfaces. Another satisfactory method is to polish the surfaces and thereafter to treat the polished surfaces with a water-proofing material such for example as a finish containing a water impermeable plastic substance in which silicon has been substituted for carbon in the molecule and which are commercially known as "silicone" resins, which are now available commercially under this name.

In order to separate the grid while frozen in the ice block from the pan 18, a sharp impact on the edge of the pan may be utilized to free the ice block and frozen grid therefrom, or the pan may be heated as by placing under the water tap so as to free the frozen ice block and the grid therefrom. In some instances I have found that a sharp impact on the vertically extending members 12 and 13 will be adequate, not only to free the grid from the frozen ice block, but also to free the grid and the block from the pan.

It is to be understood that if desired the vertically extending members 12 and 13 may be so spaced as to permit the insertion of an implement between them, which upon movement will exert a wedging action between the upstanding projection 12 and 13, causing them to pivot in the direction shown in Fig. 2. This will provide a scissor-like movement between the two members 10 and 11, resulting in shearing the ice from the surface thereof.

From the foregoing it will be understood that a grid construction embodying the present invention may be readily assembled from a plurality of parts, each of which may be separately fabricated. The parts are loosely held in their assembled relation so as to drop into position and occupy a predetermined position in the ice pan.

The present application is one of a series of three applications on ice tray grid constructions, the other two applications of this series being my co-pending applications Serial Nos. 609,525 and 609,526, filed August 3, 1945.

I claim:

1. A segmental ice tray grid comprising separate members forming an articulated longitudinal divider partition loosely joined with a plurality of articulated transverse grid members, each of said transverse grid members comprising a plurality of separate pivotally connected grid-forming members.

2. A segmental ice tray grid comprising sep-

parate members forming an articulated longitudinal divider partition, separate members forming articulated transverse members of the grid, and an elongated assembly pin loosely connected with each of said separate members.

3. A segmental ice tray grid comprising separate L-shaped members whose long arms form an articulated longitudinal divider partition loosely joined with a plurality of articulated transverse grid members, each of said transverse grid members comprising a plurality of separate pivotally connected grid-forming members.

4. A segmental ice tray grid comprising separate members forming an articulated longitudinal divider partition loosely joined with separate members forming articulated transverse members of the grid, and a vertically extending portion provided on each of said articulated members forming the transverse partitions and adapted to receive the impact of a downwardly directed blow to cause pivotal movement of said articulated transverse partition members.

5. A segmental ice tray grid comprising separate L-shaped members whose long arms form an articulated longitudinal divider partition, separate members forming articulated transverse members of the grid, and an elongated assembly pin loosely fitted in pierced openings provided in the short arms of said L-shaped members and in said separate members.

6. A segmental ice tray grid comprising separate members forming an articulated longitudinal divider partition, other separate members forming articulated transverse members of the grid, an elongated assembly pin loosely fitted in pierced openings provided in each of said separate members, and a vertically extending portion provided on each of said articulated members forming the transverse portion and adapted to receive the impact of a downwardly directed blow to cause pivotal movement of said articulated transverse partition members.

7. A segmental ice tray grid comprising separate L-shaped members whose long arms form an articulated longitudinal divider partition, separate members forming articulated transverse members of the grid, an elongated assembly pin loosely fitted in pierced openings provided in the short arms of said L-shaped members and in said separate members, and a vertically extending portion provided on each of said articulated members forming the transverse partition, and adapted to receive the impact of a downwardly directed blow to cause pivotal movement of said articulated members.

8. An articulated ice tray grid comprising segmental members loosely united by an assembly pin located near the top of said grid, said segmental members when so assembled forming an articulated longitudinal divider and a plurality of articulated transverse partitions.

9. An articulated ice tray grid comprising segmental members loosely united by an assembly pin located near the top of said grid to form an articulated longitudinal divider and a plurality of articulated transverse partitions, said segmental members forming said articulated longitudinal divider comprising separate L-shaped members, each provided with a pierced opening larger than the cross-section of said assembly pin to provide a loosely jointed assembly between said segments and said assembly pin.

10. An articulated ice tray grid comprising segmental members loosely united by an assembly pin located near the top of said grid to form an articulated longitudinal divider and a plurality of articulated transverse partitions, said segmental members forming the articulated transverse partitions each having a pierced opening larger than the cross-section of said assembly pin to provide a loosely articulated union between said segments and said pin.

11. An articulated ice tray grid comprising segmental members loosely united by an assembly pin located near the top of said grid to form an articulated longitudinal divider and a plurality of articulated transverse partitions, said segmental members forming the articulated transverse partition each having a pierced opening larger than the cross-section of said assembly pin to provide a loosely articulated union between said segments and said pin, and each having a vertically extending portion adapted to receive the impact of a downwardly directed blow to effect pivotal movement of such segment relative to the rest of the segments and relative to said pin.

12. An articulated ice tray grid comprising segmental members loosely united by an assembly pin located near the top of said grid to form an articulated longitudinal divider and a plurality of articulated transverse partitions, said segmental members forming said articulated longitudinal divider comprising separate L-shaped members, each provided with a pierced opening larger than the cross-section of said assembly pin to provide a loosely jointed assembly between said segments and said assembly pin, said segmental members forming the articulated transverse partitions each having a pierced opening larger than the cross-section of said assembly pin to provide a loosely articulated union between said segments and said pin.

13. An articulated ice tray grid comprising segmental members loosely united by an assembly pin located near the top of said grid to form an articulated longitudinal divider and a plurality of articulated transverse partitions, said segmental members forming said articulated longitudinal divider comprising separate L-shaped members, each provided with a pierced opening larger than the cross-section of said assembly pin to provide a loosely jointed assembly between said segments and said assembly pin, said segmental members forming the articulated transverse partition each having a pierced opening larger than the cross-section of said assembly pin to provide a loosely articulated union between said segments and said pin, and each having a vertically extending portion adapted to receive the impact of a downwardly directed blow and effect pivotal movement of such segment relative to the rest of the segments and relative to said pin.
